UNITED STATES PATENT OFFICE.

CHARLES C. SPREEN, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN.

UNIVERSAL BRINE-TANK SUPPORT.

Application filed December 17, 1924. Serial No. 756,514.

To all whom it may concern:

Be it known that I, CHARLES C. SPREEN, a citizen of the United States of America, and a resident of Detroit, in the county of

5 Wayne and State of Michigan, have invented certain new and useful Improvements in Universal Brine-Tank Supports, of which the following is a full, clear, and exact description.

10 In installing household refrigerating units in existing refrigerators it is found necessary to support the brine tank in the refrigerator in a large number of different ways and heretofore it has been customary

15 to attempt to provide a different type of brine tank support for each different way in which it may be desired to support the tank from the refrigerator. Obviously this requires each dealer to carry on hand an

20 enormous stock of supporting devices each type of which may be used but seldom, and therefore requires an enormous relatively idle stock which is both costly to store and difficult to maintain complete. My invention

25 provides means adapted to be fabricated in a multiplicity of different ways to provide supports of substantially every type likely to be desired. In the drawings accompanying this specification and forming

30 a part thereof I have shown, for purposes of illustration, one form which my invention may assume, and a support exemplifying the fabrication of the individual members. In these drawings:

35 Figures 1 through 3 are general views of the individual members of my supporting means.

Figure 4 is an enlarged view showing in a general way the manner in which these 40 members may coact, while

Figures 5 and 6 are front and rear views of the illustrated way in which these members may be fabricated into a brine tank support.

45 The individual members herein shown comprise strips 11 each provided with a plurality of holes 12 and so formed that it may be cut off at any desired length by tools which may be readily carried by the work-

50 men to the place where the brine tank is being installed, L-shaped members 13 each reenforced by side flanges 14 and provided with a plurality of apertures 15 in its short arm 16 and an elongated aperture 17 in its long arm 18, and brine tank seat members

19 each comprising a base 20 carrying up-standing flanges 21 and 22 and provided with an aperture 23 arranged to receive a suitable securing means.

The general manner in which these parts 60 may coact is illustrated in Figure 4 wherein the short arm 16 of the L-shaped member 13 is secured to the refrigerator wall 24 by means of screws 25 passing through two of the apertures 15, and the long arm 18 of the 65 L-shaped member 13 is secured, to a seat member 19 engaging one corner of the brine tank 26, by means of a bolt 27, passing through the aperture 23 in the seat member 19 and the elongated slit 17 in the long arm 70 70 of the L-shaped member 13, and also passing through one of the apertures 12 and thus securing a strip 11 extending to the means supporting an adjacent corner of the 75 brine tank 26.

In Figures 5 and 6 I have shown a support wherein one corner of the brine tank is supported from one side of the brine tank chamber and steadied at the top from this same side of the brine tank chamber, wherein another corner of the brine tank is supported from both the top and bottom of the brine tank chamber and steadied at the top by a brace extending over from the supporting strut, wherein a third corner of the brine 80 tank is supported from the side wall of the brine tank compartment and the top wall of the brine tank compartment, and wherein the fourth corner of the brine tank is supported from the bottom wall of the brine 85 tank compartment and braced from the side wall of the brine tank compartment.

In more detail, the support of the left front corner of the brine tank (at the left in Figure 5) comprises a pair of L-shaped 90 members 13^a and 13^b having their short arms 16^a and 16^b secured to the brine tank side wall 29 by means of screws 25^a and their long arms 18^a and 18^b secured back to back by means of a bolt 28^a which also connects these long arms 18^a and 18^b through strips 11^a and 11^b to a seat 19^a engaging one corner of the brine tank 26 and the long arm 18^c of an L-shaped member 13^c having its short arm 16^c connected by means of bolts 28^b to a strip 11^b which is in turn secured at its upper end by means of bolts 28^c to the long arm 18^d of an L-shaped member 13^d the short arm 16^d of which is secured, by means of a bolt 28^d, to a seat 19^b engaging the ad- 100 105 110

ja⁵cent corner of the brine tank 26, to strips 11^e and 11^f, and to the long arms 18^e and 18^f of a pair of L-shaped members 13^e and 13^f arranged with their long arms 18^e and 18^f lying back to back and with their short arms 16^e and 16^f secured to the brine tank chamber side wall 29 by means of screws 25^b.

The support for the right front corner 10 of the brine tank (at the right in Figure 5) comprises an L-shaped member 13^g having its short arm 16^g secured by means of screws 25^c to the bottom wall 30 of the brine tank compartment and its long arm 18^g secured 15 by means of bolts 28^c to the short arms 16^h and 16ⁱ of a pair of L-shaped members 13^h and 13ⁱ which have their long arms 18^h and 18ⁱ secured together back to back through the strips 11^a and 11^b by means of 20 bolts 28^c one of which also secures to the support a seat 19^g engaging the adjacent corner of the brine tank 26. The bolts 28^c also secure to the long arm 18^g of the L-shaped member 13^g and the short arms 16^h and 16ⁱ 25 of the L-shaped members 13^h and 13ⁱ the lower end of a strip 11^d the upper end of which is secured by means of bolts 28^g to the long arm 18^j of an L-shaped member 13^j the short arm 16^j of which is secured by 30 means of a long bolt 31 to the top wall 32 of the brine tank chamber. Secured to the strip 11^d intermediate its ends and by means of bolts 28^h is the long arm 18^k of an L-shaped member 13^k the short arm 16^k of which is secured by 35 a bolt 28^l to the strips 11^e and 11^f and to the seat 19^d engaging that corner of the brine tank 26.

The right rear corner of the brine tank 40 (at the left in Figure 6) is supported by a pair of L-shaped members 13^l and 13^m having their short arms 16^l and 16^m secured by means of screws 25^d to the brine tank chamber side wall 33 and their long arms 18^l and 18^m secured back to back by means of bolts 28^l to strips 11^e and 11^k, a seat 19^e engaging the adjacent corner of the brine tank 26, and the long arm 18ⁿ of an L-shaped member 13ⁿ the short arm 16ⁿ of which is secured by 45 means of a bolt 28^k to the lower end of a strip 11^f, the intermediate portion of which is secured by means of bolts 28^l to the long arm 18° of an L-shaped member 13° the short arm 16° of which is secured by means of a 50 bolt 28^m to strips 11^g 11^l and to a seat 19^f engaging the adjacent corner of the brine tank 26, while the upper end of the strip 11^f is secured by means of bolts 28ⁿ to the long arm 18^p of an L-shaped member 13^p the short arm 16^p of which is secured by 55 means of screws 25^e to the top wall 32 of the brine tank chamber.

The support for the left rear corner of 60 the brine tank (at the right in Figure 6) comprises an L-shaped member 13^q having

its short arm 16^q secured by means of screws 25^f to the bottom wall 30 of the brine tank chamber and its long arm 18^q secured by means of bolts 28° through a strip 11^h to the short arm 16^r of an L-shaped member 13^r the long arm 18^r of which is secured by means of bolts 28^p to the strips 11^e and 11^f and to a seat 19^g engaging the adjacent corner of the brine tank 26. The upper end of the strip 11^h is secured by means of bolts 28^q to the long arm 18^g of an L-shaped member 13^g the short arm 16^g of which is secured by means of a bolt 28^r to a seat 19^h engaging the adjacent corner of the brine tank 26, the adjacent ends 75 of the strips 11^g and 11^h, and the long arms 18^t and 18^u of a pair of L-shaped members 13^t and 13^u the short arms 16^t and 16^u of which are secured by means of screws 25^g to the side wall 29 of the brine tank 80 chamber.

The strips 11^a, 11^b, 11^c, and 11^d, and the strips 11^e, 11^f, 11^g, and 11^h, obviously form frames at the bottom and top of the brine tank, respectively, effective to prevent displacements of the seats 19, while the strips 11^a and 11^b also serve to support, by means of bolts 34, a shield 35, arranged to prevent fluid dripping through the aperture 36 in the brine compartment bottom wall 30. 95

It will be apparent to those skilled in the art that the support herein illustrated is formed from the three parts above described and completely supports the brine tank from the brine chamber. It will also 100 be apparent that many of the parts in this support may be omitted to form other supports which will also support the brine tank satisfactorily if not so completely, and at the same time that additional parts may 105 be added to even more completely support the tank. It will also be apparent that the supporting parts may be combined in very many ways other than that therein shown and in general it will be obvious to those skilled in the art that a plurality of the three parts herein disclosed may be combined to support a brine tank in substantially any manner in which anyone may desire the tank to be supported. It will therefore be obvious to those skilled in the art 110 that my invention does provide a simple group of members adapted to be combined to form substantially any type of brine tank support which may be desired under any circumstances, and therefore prevents and eliminates the necessity of maintaining on hand the large variety of supports and supporting material now customarily stocked. It will also be apparent to those skilled in the art that the embodiments of my invention herein shown comprise advantages other than those which I have 115 specifically pointed out and also that the embodiments of my invention herein shown 120 125 130

may be variously changed and modified without departing from the spirit of my invention or sacrificing the advantages thereof. It will therefore be understood that this disclosure is illustrative only and that my invention is not limited thereto.

I claim:

Means, for supporting a brine tank from the interior of a refrigerator, comprising a plurality of seat members disposed about and engaging the edges of said tank, a plurality of L-shaped members each having one arm connected to one of said seat mem-

bers and the other arm connected to a supporting member, a plurality of adjustable strip members, comprising such supporting members, and connecting said seat members and said L-shaped members into a complete support for said tank, and means securing together said seat members and L-shaped members and strip members into such complete support.

In testimony whereof, I hereunto affix my signature.

CHARLES C. SPREEN.
